(57) **CLAIM**

I claim the ornamental design for an interactive memorial, as shown and described.

DESCRIPTION

FIG. 1 is a front perspective view of the interactive memorial of the present invention;

FIG. 2 is a back perspective view of the interactive memorial of the present invention;

FIG. 3 is a front elevational view of the interactive memorial of the present invention;

FIG. 4 is a right hand side elevational view of the interactive memorial of the present invention;

FIG. 5 is a left hand side elevational view of the interactive memorial of the present invention;

FIG. 6 is a rear elevational view of the interactive memorial of the present invention;

FIG. 7 is a top view of the interactive memorial of the present invention; and,

FIG. 8 is a bottom view of the interactive memorial of the present invention.

The broken line depict portions of the interactive memorial that form no part of the claimed design.

1 Claim, 6 Drawing Sheets
